UNITED STATES PATENT OFFICE.

JOSEPH L. NYLANDER, OF SEATTLE, WASHINGTON.

BED-LIFTER.

1,170,929.

Specification of Letters Patent.

Patented Feb. 8, 1916.

Application filed March 29, 1915. Serial No. 17,921.

To all whom it may concern:

Be it known that I, JOSEPH L. NYLANDER, a citizen of the United States, residing at Seattle, in the county of King and State of Washington, have invented a new and useful Improvement in Bed-Lifters, of which the following is a specification.

My invention relates to improvements in bed lifters and the object of my improvement is to provide a device of neat appearance and simple construction that may be used to lift and sustain in a lifted position the head or the foot of a bed.

The invention consists in the novel construction, adaptation, and arrangement of parts more fully described in the following specification, illustrated in the accompanying drawings and finally pointed out in the appended claims.

Referring to the accompanying drawings Figure 1 is a view in perspective of a bed lifting device embodying my invention; Fig. 2 is a view in front elevation of the same as it may appear when in use; Fig. 3 is a view in end elevation of the same; Fig. 4 is an enlarged view in vertical section on broken line 4, 4 of Fig. 2, showing certain parts in elevation; Fig. 5 is a view in perspective of a detail of my invention; Fig. 6, 30 is a plan view of a ratchet lever, certain parts being broken away more clearly to illustrate certain other parts; and Fig. 7 is a view in end elevation of a modified form of lifting device that may be embodied in my invention.

This invention is particularly adapted for use in hospitals or in sick rooms where a patient is confined in bed and it is desired to raise one end of the bed to change the position of the patient from a horizontal to an inclined plane.

Referring to the drawings, throughout which like reference numerals indicate like parts, 8 is the base plate of a bed lifter and 45 9 are parallel, spaced rack bars that are arranged in pairs at each end of the base plate and are connected with base blocks 10 by which they may be secured in a vertical position on the base plate 8. The top end of 50 each pair of bars 9 are connected by cross pieces 11 which project outwardly at one side and are secured to a brace rod 12 that extends lengthwise of the top portion of the bed lifter to serve as a brace and to tie the 55 two pairs of bars at opposite ends of the frame together. Each pair of bars 9 is pro-

vided with a slotted cross block 13, that carries a worm wheel 14 which is mounted on a vertical shaft 15 and is adapted to engage with the teeth on the rack bars 9 to move 60 the block 13 vertically thereon.

The lower end of each shaft 15 is provided with a bevel gear wheel 16 that meshes with another bevel gear wheel 17 that is secured to a horizontal shaft 18 whereby the worm 65 wheel 14 may be retarded, the horizontal shaft 18 being journaled in downwardly projecting bearing brackets 19 formed integral with the cross blocks 13 and having cross pins 20 that are adapted to be engaged 70 by a ratchet lever 21 provided in the ends thereof.

The cross blocks 13 are each provided on their inner sides with spaced lugs 22 having inwardly projecting stud pins 23 disposed 75 therebetween, and a horizontal bed support 24 formed of parallel flat bars secured at each end to spacing blocks 25 extends between the blocks 13 and is supported on the stud pins 23 which project into holes in the 80 blocks 25, as more clearly shown in Fig. 4, the ends of the bed support 24 being disposed between the spaced lugs 22 whereby such bed support is permitted to oscillate 85 slightly on the lugs 22.

The bed support 24 is provided at one end with fixed recesses 26 of a suitable shape to receive the casters 27 of a bed 28 and at the other end with a movable caster receptacle 29, more clearly shown in Fig. 5, 90 that may be adjusted lengthwise of the support 24 to adapt the device to be used on beds of different width.

The ratchet lever 21 is provided with an enlarged end portion that is bifurcated to 95 form side plates 30 between which are journaled a ratchet wheel 31 that is engaged by a spring pressed pawl 32 and is formed with hub portions 33 that project outwardly in opposite directions through the side plates 100 30 and are provided with slots 34 that engage with the pins 20 whereby the shaft 18 may be turned.

In Fig. 7 I have shown, by a view in end elevation, a modified form of my invention comprising parallel spaced bars 35 arranged in pairs in the same manner as the rack bars 9 and provided with slotted cross heads 36, only one of which is shown, movable vertically thereon and threaded to receive vertically disposed adjustment screws 37 that are disposed between the bars 35 in parallel re-

lation thereto and are provided on their bottom ends with bevel gear wheels 38 that mesh with other bevel gear wheels 39 on a shaft 40 that corresponds with the shaft 18 and may be rotated in a similar manner by the ratchet lever 21 to raise and lower the cross heads 36, a bed support similar to the support 24 being connected with such cross heads 36.

- 10 The operation of this invention is as follows: The device is placed crosswise of the end of the bed that is to be elevated, with the bed supporting bar 24 in its lowermost position and the end of the bed is lifted and 15 the casters are placed in the caster receptacles 26 and 29 respectively. The end of the bed may then be raised to any desired height by placing the ratchet bar 21 on the shaft 18 and turning such shaft in the 20 proper direction to cause the worm wheels 14 to move upwardly on the rack bars 9. The bed will then remain in the position in which it is set until the worm wheel is again rotated by turning the shaft 18. As 25 the bed is raised and the head panel of such bed assumes an angular position the supporting bar 24 will rotate slightly on the pins 23 thus preventing a twisting strain from being sustained by the bed lifter on the bed 30 frame.

The operation of the device shown in Fig. 7, is similar to the operation hereinbefore described, the shaft 40 being turned to rotate the screws 37 and the screws 37 moving 35 the crossheads 36 up or down on the bars 35.

The ratchet associated with the ratchet bar 21 is single acting but the slots 34 on both ends of the outwardly projecting hub 33 permit such bar to be turned over when 40 it is desired to reverse the direction of rotation of the shaft 18.

Manifestly, changes in the form of construction and arrangement of the various parts embodied in my bed lifting device 45 may be made without departing from the spirit of my invention or sacrificing any of its advantages.

Having described my invention what I claim as new and desire to secure by Letters 50 Patent is:—

1. A bed lifter of the class described, comprising a frame having vertically movable blocks associated therewith, a bed supporting bar pivotally connected with said blocks 55 to permit a slight oscillation of said bar and means for adapting said bar to be engaged with beds of different width.

2. A bed lifter of the class described comprising a frame having two pairs of vertical spaced bars disposed at opposite ends thereof, blocks slidably mounted on each of 60

said pairs of bars, means for raising and lowering said blocks, and a bed supporting bar connected with said blocks to support one end of a bed in an elevated position. 65

3. A bed lifter of the class described, comprising a base plate, a pair of vertically disposed toothed rack bars secured in spaced relation at each end of said base plate, blocks 70 slidably mounted on each pair of said rack bars, vertical shafts associated with said blocks, worm wheels provided on said vertical shafts and adapted to engage with teeth on said rack bars, a horizontal shaft 75 extending lengthwise of said base plate and journaled in said blocks, bevel gears connecting said vertical shafts and said horizontal shaft whereby said worm wheels may be rotated to move said blocks simultaneously, 80 and a bed supporting bar connected with said blocks.

4. A bed lifter of the class described comprising a frame, vertical standards provided at the ends of said frame, a bed supporting 85 member having one end connected with each of said vertical standards and means for simultaneously moving the two ends of said bed supporting member vertically on said standards at the same rate of speed. 90

5. A bed lifter, comprising a base plate, pairs of parallel vertical toothed rack bars secured in spaced relation at each end of said base plate, blocks slidably associated with each of said pairs of rack bars, vertical 95 shafts journaled in said blocks, worm wheels secured on said vertical shafts, said worm wheels being adapted to engage with the teeth on said rack bars, bevel gears connecting said vertical shafts with a horizontal 100 shaft whereby said blocks may be moved simultaneously in a vertical direction on said rack bars, a bed supporting bar extending between said blocks to support the end of a bed, said bed supporting bar being pivotally 105 connected with said blocks to permit a slight oscillation of said bar, and means for adapting said bar to engage with beds of various width.

6. A bed lifter of the class described, comprising a frame, a pair of spaced vertical bars at each end of said frame, blocks slidably associated with each pair of said bars, screws to move said blocks vertically on said bars, and a bed supporting bar connected with said blocks to support one end of a bed. 110 115
